UNITED STATES PATENT OFFICE.

PETER PAUL COLER, OF CLYMAN, WISCONSIN.

GRAIN-BINDER.

SPECIFICATION forming part of Letters Patent No. 341,131, dated May 4, 1886.

Application filed June 22, 1883. Serial No. 99,017. (Model.)

To all whom it may concern:

Be it known that I, PETER PAUL COLER, a citizen of the United States, residing at Clyman, in the county of Dodge and State of Wisconsin, have invented certain new and useful Improvements in Grain-Binders; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

Figure 1 is a plan view of my machine. Fig. 2 is a rear end elevation of the same, showing the binder-arm in its lowest position. Fig. 3 is a similar view, showing the binder-arm in its highest position. Fig. 4 is a rear face view of the gear-wheel a^5 ; Fig. 5, an outer edge view and a front face view of the disk d and its pawl. Fig. 6 is a perspective view of the lever for throwing out of gear the clutch on the packer-shaft. Fig. 7 is an elevation of the outer or discharging side of the binder. Fig. 8 is an elevation of a portion of the forward end of the same. Fig. 9 is a rear side view of the binder-arm, showing also other parts. Fig. 10 is an edge view of the same. Fig. 11 is an inner or front side view of the heel of the binder-arm, showing the device for actuating the finger. Fig. 12 is a similar view of the lug with its eccentric slot for operating said finger. Figs. 13 and 14 are inner edge views of the cam and gear wheels for operating the knotter and cutting and holding mechanisms. Fig. 15 is a similar view of the same, partly in vertical section, showing also the knotter and the arm for withdrawing the compressors. Fig. 16 is a side elevation of one of said gear and cam wheels. Fig. 17 is an elevation of the cutting and holding device, with part of the outer plate, m^3 , broken away. Fig. 18 is a plan view, partly in section, of the same. Fig. 19, Sheet 2, is a plan view of the presser-bar. Fig. 20, Sheet 2, is a side elevation of the lower ends of the knotter-shafts and knotter-hooks. Fig. 20 a , Sheet 2, is an end view of the knotter-hooks. Figs. 21 and 21 a , Sheet 3, are plan views of the same, showing the shafts in cross-section. Fig. 22, Sheet 4, is a detail view of the packers and the

mechanism for raising the outer compressors. Fig. 23, Sheet 4, is a side elevation of the packers, the packer-shaft, and the clutch mechanism. Fig. 24, Sheet 4, is a similar view of the clutch. Fig. 25, Sheet 4, is a plan view of the breast-plate. Fig. 26, Sheet 2, is a plan view of the swinging arm below the knotter-jaws, and Fig. 27, Sheet 4, is an inverted plan view of the knotter-jaws and the spring stop-arm. Figs. 28, Sheet 4, are top plan views showing the manner of opening and closing the jaws.

This invention consists, first, in having the platform of the machine so constructed and arranged that it may be raised or lowered to regulate the size of the bundle; second, in a compressor-bar arranged below the tying mechanism and adapted to be raised by the binder-arm to compress the bundle; third, in so constructing the grasper that it will hold automatically any size of cord; fourth, in a stripping-hook for taking the loop off the knotter; fifth, in the peculiar construction of the knotter; sixth, in a trip and combined mechanism for stopping the packers at the instant the binding mechanism begins to operate; seventh, in the mechanism whereby the packers are set in motion and the binding mechanism stopped; lastly, in other constructions and arrangements of parts, as hereinafter fully described, and particularly pointed out in the claims.

In the accompanying drawings, A is the frame of the machine, to which the various parts of the invention are secured.

a is the main driving-shaft, on which are fixed one or more sprocket or other suitable wheels, a' , by means of which and an endless chain or belt the binding mechanism may be actuated from the reaper driving mechanism. A driving-pinion, a^2 , fixed on the main shaft meshes with a loose sliding gear-wheel, a^3 , on the packer-shaft a^4 , and also with a gear-wheel, a^5 , turning loosely on the shaft a^6 , which imparts motion to the binding mechanism. The gear-wheel a^5 is provided on its rear or inner side with a clutch, a^7 , which engages at the proper time a clutch, a^8 , fixed on the packer-shaft a^4 . The wheel a^5 is pressed by a spring, a^9 , into engagement with the clutch a^8 , and it is forced out of engagement therewith by one end of a lever, a^{10} , pivoted at its central part

to the frame of the machine, the opposite end of which lever is actuated as hereinafter explained. The inner or rear end of the packer-shaft a^4 is provided with two cranks, a^{11} a^{12} , 5 on which the reciprocating packers a^2 are journaled. The cranks are so arranged that they give an alternate movement to the packers. The packers at their upper ends are provided with slots, which engage the fixed pin or rod b , whereby the movement of the lower ends of the packers is controlled in such a manner that they engage the grain delivered from the harvester, move it toward the binder mechanism, and then draw upward out of contact 10 with it. The pin b has one of its ends fixed to the frame of the machine.

b' is a standard pivoted on the rod b between the upper ends of the packers, and it has made fast to it one end of an arm, b^2 , on 15 the other end of which are pivoted, near their upper ends, the outer compressor-arms, b^3 , against which the grain is pressed by the packers, said arm being bent in to meet the arm b^2 at their common pivotal point. The 20 arm b^2 passes through a sleeve, b^4 , fixed on one end of a lever, b^5 , which has its other end pivoted on a rock-shaft, c . The lever b^5 is lifted by a cam, hereinafter described, and thereby the compressors b^3 are raised, so that 25 the bound bundle can be discharged at the outer side of the platform. The lower ends of the compressors b^3 extend down nearly to the platform, and are adapted to yield to a certain degree to the pressure of the grain by 30 means of the spring b^6 on the rod b^7 , which is pivoted to an upward extension of their united upper ends. Said spring bears against a nut on the bar b^7 , and is compressed against a standard rising vertically from the arm b^2 .

35 The rock-shaft C has fixed upon it two cam-arms, c^1 c^2 , located in such a position that the compressor-arms b^3 may come in contact therewith and move them outwardly, and thus rock the shaft c .

40 On the outer or forward end of the rock-shaft c there is fixed a bent trip-lever, c^3 , one arm of which is arranged to come in contact with a pivoted pawl, d^3 , hereinafter described, while its other arm is placed on a rod, c^4 , which 45 has its lower end fixed to the lever d^3 , hereinafter described. Around this rod c^4 is coiled a spring, c^5 , which acts against the arm of the trip-lever c^3 , and thus raises the trip-lever out of engagement and restores the rock-shaft c to 50 its normal position.

55 The principal parts of the binding mechanism are operated by the shaft a^6 , journaled in the upper part of the supporting-frame A. Near the outer or forward end of said shaft, 60 inside of the gear-wheel a^5 , there is fixed a disk, d , on the outer face of which is pivoted the U-shaped pawl d^3 , which is controlled by a spring, d^6 , fixed to the rim of said disk. The rim of the disk has formed in it a cam-notch, d^7 , having one of its edges properly inclined, into 65 which notch the inner end of the clutch-shifting lever a^{10} drops. The opposite or outer end

of said lever is extended to and bears against the rear side of the gear-wheel a^5 , as heretofore described.

70 When the inner end of the lever a^{10} is forced out of the notch d^7 , the wheel a^5 will be forced against the spring a^9 and be disengaged from the clutch a^8 on the packer-shaft. When the disk d rotates and brings the cam-notch opposite the inner end of the lever a^{10} , the end of the lever enters the notch, and the spring a^9 forces the gear-wheel a^5 back into engagement with the clutch a^8 , and the packers are set in motion.

75 The large gear-wheel a^5 has three pins, d^1 , arranged about equidistantly around its center, and projecting at right angles inward toward the disk d . One or the other of these pins engages the inner edge of the pawl d^3 , which latter, being pressed down on the pins by the spring d^8 , locks the wheel a^5 and the disk d together. At the proper moment the trip-lever 80 c^3 is brought down, and the outer end of the pawl d^3 , as the disk d rotates, comes in contact with said trip-lever, and the pawl is thereby forced outward against the spring d^8 and is disengaged from the pin d^1 , thus unlocking the disk d from the wheel a^5 . When the wheel a^5 and disk d are locked together, the shaft a^6 85 will revolve, and when they are unlocked the shaft will remain stationary, while the wheel a^5 , which is mounted loosely thereon, will continue to rotate. The unlocking of the shaft and disk takes place whenever the compressor-arms b^3 rock the shaft c by depressing the cam-arms c^1 c^2 , for as the lever c^3 is fixed on the end of said shaft its arm toward the pawl will be depressed, and will bear upon and move the end of the pawl outward, as above described. 90

95 It will be seen that the described mechanism is so arranged that the shafts a^6 and a^4 are alternately engaged and disengaged from the driving-shaft, so that when the packers are in motion the binding mechanism is stationary, 100 and when the latter is in operation the former are at rest.

105 A rock-shaft, d^8 , is journaled in the frame below the outer or delivery side of the binder-platform, and carries on its inner or rear end the binder-arm k , hereinafter described. Said rock-shaft has fixed on its outer or forward end a segment-pinion, d^9 , which is engaged by a segment-rack, d^{10} , on the lower end of the 110 rocking arm d^8 , which is pivoted on the frame A. The arm d^8 is also provided with a smooth segment or delay-surface, d^9 . The upper end of the rocking arm is provided with a slot, d^{11} , in which is placed a sliding bearing, d^{12} , through which passes the wrist-pin c^6 of the crank c^5 , fixed to the outer or forward end of the binder-shaft a^6 . The gear-wheel a^5 is situated between the crank c^5 and the disk d . When the shaft a^6 rotates, the crank c^5 rocks the lever or arm d^8 on its pivoted center, and thereby the shaft d^8 is rocked so as to raise and lower the binder-arm. 115

120 Near the inner or rear end of the shaft a^6 is fixed a cam and gear-wheel, e . In the for-

ward edge of the rim of the wheel is formed a notch, e' , opposite which stands a lug, e'' , which is so formed and placed as to make with the notch e' a curved cam-groove, e^3 , between it and the rim of the wheel. On the opposite side of the rim of the wheel are two cogs or teeth, e^4 , which engage at the proper time with the knotter-pinion. On the inner or rear surface of the wheel e is formed a cam-groove, e^5 , into which one end of a pin, b^9 , fixed transversely through the arm b^5 enters. Another wheel, e^6 , is fixed on the shaft a^6 to the rear of and near the wheel e . The wheel e^6 has a part of the forward edge of its rim formed into a rack, e^7 , facing the wheel e , and is provided with a cam-groove, e^8 , similar and opposite to the cam-groove e^5 in the wheel e , into which cam-groove e^8 the opposite end of the pin b^9 enters. The arm b^5 is raised by the pin b^9 and the cam-grooves e^5 and e^8 , and by this means the compressor-arms are lifted up from the platform, so as to permit the bundles to be discharged below them. The segment-rack e^7 and the cogs e^4 consecutively engage the knotter-pinion. The segment-rack rotates said pinion in one direction, and upon disengaging from it the teeth e^4 give said pinion a partial reverse rotation.

A discharging-arm or kicker, f , is fixed on the inner or rear end of the shaft a^6 , and is so placed thereon that it throws the bundle after it has been bound from the platform.

The platform g is made in two sections, g^1 and g^2 . The inner section, g^1 , is fixed, and the grain is discharged upon it from the reaper. The outer section, g^2 , is hinged to the outer edge of the section g^1 , and may be raised or lowered, so as to vary the space between it and the curved breast-plate g^3 , according to the amount of grain which it is desirable to make into a bundle. By raising the section g^2 the binder-arm has to move the presser-arm g^4 , now to be described, through a shorter distance. A transverse slot, g^4 , is formed in the platform running across both sections and situated vertically below the knotting mechanism. A longitudinally-slotted vibrating presser-bar, g^5 , swings in the slot g^4 , and has its inner end hinged to the lower surface of the fixed section g^1 of the platform, while its outer end is free, so that it can be raised to compress the bundle between it and the lower surface of the fixed breast-plate g^3 . The outer end of the presser-bar has a plate extending outward and resting upon the upper surface of the section g^2 , thus keeping the presser-bar from falling through the slot g^4 . The presser-bar is raised by the binder-arm, which passes through its slot, a pin, i , which passes through said arm, and is hereinafter more fully described, coming in contact with the lower edges of the presser-bar.

The section g^2 of the platform may be set at any desired inclination by means of adjustable supports g^6 g^7 , held in the framing below the platform.

The twine-box h is mounted upon a standard,

h' , secured at or near one of the outer corners of the platform, so as to be entirely out of the way of the grain as the latter is carried through the binder. Said twine-box is provided with a glass front, h^2 . The box is made water-proof, so that the ball of twine will be kept perfectly dry. Through the bottom of the box a suitable hole is made, through which the twine is drawn. A tension-pulley, h^3 , is placed below the twine-box, and held in position by a bracket, h^4 , having a pin on which the pulley rotates. A coiled spring surrounds the pin, and bears against the bracket h^4 at one end and against the side of the pulley at the other, and the friction caused by the spring retards the rotation of the pulley and gives the necessary tension to the cord. The tension is regulated by the nut on the end of the pin.

A guide-pulley is journaled in a suitable bracket fixed near the bottom of the standard h' .

The binder-arm k is composed of the two similar and parallel bars, k^1 k^2 , placed side by side, and secured firmly together at suitable points. The bars at their united outer ends are formed into a solid point, k^3 , for piercing the grain. Small anti-friction guide-rollers k^4 , k^5 , and k^6 are pivoted between the bars k^1 k^2 , over which rollers the cord passes on its way from the twine-box to the holding and knotting mechanisms. The bars k^1 k^2 of the binder-arm have made in one piece therewith the brace-rods k^{10} , which, when the said arm is in its lowest position, first run downward from a point a short distance below the rock-shaft d , and then curve upward and inward until they meet and join the parts k^1 , and thus form the separator k^9 .

k^7 is the elbow formed where the brace-rods k^{10} turn upward to form the separator k^9 .

The roller k^4 is pivoted between the bars k^1 k^2 , near the point of the binder-arm, the roller k^5 a short distance above the elbow k^7 , and the roller k^6 at a proper point between the rollers k^4 and k^5 .

By the described construction and arrangement the binder-arm may be made very light and strong, and the wear and tear avoided which would result if the arm were made of one piece of metal heavy enough to give the requisite strength.

An arm or finger, k^{11} , is pivoted between the side bars of the binder-arm on a pin, i , the ends of which project outward on opposite sides of the binder-arm to raise the presser-bar g^5 , hereinbefore described. The end i' of this finger is made slightly hooked, and in the operation of the machine it is thrown outward, as hereinafter described, and presses the cord just below the knotter, for the purpose hereinafter described.

When the binder-arm is swung down below the platform, and while the grain is being packed to form a bundle, the finger k^{11} is drawn in between the bars of said arm out of the way. It is turned outward by the following means: A slotted sliding bar, k^{12} , has one end pivoted

to the end of the finger and its other end longitudinally slotted at i^6 . The binder-arm rock-shaft d^5 passes through the slot and supports the bar k^{12} . The said bar is provided 5 with a pin, i^7 , which enters an eccentric slot, i^8 , formed in a lug, i^4 , fixed on the end of the sleeve or bearing i^5 , which supports the binder-arm rock-shaft d^5 . As the binder-arm is thrown up, the cam-slot acts through the pin 10 i^7 to slide outward the bar k^{12} , which turns out from the binder-arm the free end i^9 of the finger k^{11} .

When the binder-arm is thrown up in the act of binding a bundle, the lever d^8 swings 15 outward, as shown in dotted lines in Fig. 8, and the delay-segment d^9 slides on the ends of the two inner cogs of the segment-pinion d^6 , thus allowing the crank c^5 to continue its revolution without further moving the binder- 20 arm rock-shaft, but holding the said shaft and binder-arm firmly and steadily in place while the knotter is in operation and the knot is being tied.

The grasper m , for holding the end of the 25 cord, is composed of a hook, m^1 , pivoted between two parallel plates, m^2 and m^3 , lying close together and supported by the parallel rods m^4 , which pass through said plates. A suitable opening, m^7 , is made in the plate m^2 , and a notch similar to the lower part of said opening 30 is made in the upper edge of the plate m^3 , the opening and notch being for the passage of the point of the binder-arm. Spiral springs m^5 surround the rods m^4 , and are suitably 35 held so as to bear against the plates m^2 and m^3 to press them together, while permitting them to yield slightly to different thicknesses of cord. The inner plate, m^2 , is extended upward, as shown, and has pivoted to it the 40 shank of the hook m^1 . Said shank extends upward from its pivotal connection, and has standing at right angles from its inner surface the pin m^6 , the projecting end of which bears against the side of the rim of the wheel e , and 45 is drawn into the cam-groove e^2 by the lug e^2 . The rim of said wheel bearing against said pin m^6 retains the hook m^1 in the position shown in full lines in Fig. 17. When the pin 50 passes through the cam-groove e^2 , the hook m^1 is moved across the opening m^7 , as shown in dotted lines, and then immediately returned to its first position. A knife, m^8 , is placed on 55 the inner plate, m^2 , on the side adjacent to the hook m^1 . The hook and hook-bar bear against the side of the knife, and are held against it by the pressure of the springs m^5 . The knotter n is supported on a hollow shaft, n' , set in a nearly-vertical position and standing close to the track of the binder-arm. The hollow shaft 60 n' has on its upper end the pinion n^2 , situated between the lower portions of the wheels e and e' , and actuated by one or the other at the proper time. The pinion is rotated in its direct movement by the segmental rack e^1 on the 65 wheel e^6 , and is immediately afterward partly rotated in the opposite direction by the two

teeth e^4 on the wheel e . The inner shaft, n^3 , passes through the hollow shaft n' , extends above the pinion n^2 , and is surrounded above said pinion by a coiled spring, n^4 , held in place 70 by a suitable nut, as shown. The two shafts are properly supported in a depending sleeve-bearing, n^5 . The spring n^4 allows a certain amount of vertical motion to the shaft n^3 , and presses the two knotter-hooks together with a 75 yielding pressure, so as to properly hold cord of varying thickness.

The knotter consists of two parts—a horizontal hook-jaw, o , fixed on the end of the hollow shaft n' , and a plate, o' , fixed to the 80 end of the inner shaft, n^3 , and having on one side the hook-jaw o^2 , to co-operate with the hook-jaw o . Between these two jaws o and o^2 the cord is grasped during the operation of tying the knot. On the other side of the plate 85 o' is formed the wing o^3 , which curves upward in the form shown in Fig. 3, so as to slip over the cord and cause it to pass under the knotter. The plate o' is limited in its movement on the hook-jaw o by the curved slot o^4 , formed in 90 the plate concentric with its center of motion, and the pin o^5 , projecting downward from the jaw o through said slot. The plate and jaw move on each other to allow the jaws o and o^2 to open and grasp the binding-cord at the 95 proper time. A spring, o^6 , is attached at one end to the frame of the machine, and has its other or free end so situated as to come in contact with a lug, o^7 , on the upper edge of the wing o^3 when the knotter has been rotated 100 by the segment-rack e^1 and the loop has been formed round the jaws. This contact detains the jaw o^2 , while the other jaw continues its motion for a short distance, thus separating the jaws o and o^2 , so that they may receive the 105 ends of the cord outside of the loop which has been formed around the jaws by the rotation. At the end of this rotation the lug o^7 slips over the spring o^6 . The knotter is then given a partial rotation by the teeth e^4 110 on the wheel e engaging the knotter-pinion. The lug o^7 again comes in contact with the spring o^6 , and the jaws are thus closed upon the cord. When the spring o^6 slips over the lug o^7 , it makes a ringing sound, indicating 115 that the tying operation is nearly over and that the cord around the bundle just formed is about to be separated from the ball of twine, the cutting mechanism being arranged to act as soon as the knotter-jaws have grasped the 120 cord.

An oscillating bar, s , is pivoted at s^5 to the frame in such a position that its inner or forward arm swings just below the knotter. Its outer or rear arm, s' , is bent outward, and in its 125 normal position lies in a line slightly inclined to the direction of the movement of the grain through the machine and across the path of the rear compressor-arm, b^3 . A stripper-hook, s^2 , is pivoted to the inner end of the bar s , and is 130 pressed by spring s^3 against the small pin s^4 . The spring allows the hook to yield to pass

over the cord, so that it can engage the cord on its return movement and strip off the loop from the knotter-jaws.

The arm s' of the bar s is so constructed and 5 situated that it will be engaged and pressed to the rear by the rear compressor-arm, b^3 , which will cause the hook s^2 to swing slightly and pass over the cord. As the discharging-arm f moves outward to discharge the bundle off 10 the platform, it strikes the rear edge of the arm s' , and returns the bar s to its first position. In this movement the hook s^2 seizes the cord and strips the loop from the knotter-jaws over the ends of the cord held in the jaws, and 15 completes the knot. At the same time the cutter severs the cord. The bar s lies just outside of the path of the binder-arm, and when the latter ascends the finger k^{11} brings the two 20 portions of the cord which passes around the bundle together, and holds them against the lower surface of said bar s while the tying mechanism is in action.

The operation of the machine is as follows: 25 The grain from the reaper is fed onto the section g' of the platform, and is conveyed by the packers under the breast-plate g^2 , and against the cord v and the compressor-arms b^3 . These compressor-arms yield to the pressure of the grain, and when the proper quantity to form 30 a bundle has accumulated they will be forced back sufficiently to bear against the cam-levers $c' c'$, and thereby turn the rock-shaft c and the attached trip-lever c^2 . The trip-lever will thus be lifted from the pawl d' , so that the 35 latter will drop and be engaged by one of the pins d^4 on the wheel a^5 , thus putting the disk d , and consequently the shaft a^6 and the binding mechanism, in motion. The size of the 40 bundle is regulated by the position of the hinged platform g^2 . When it is desired to make the bundles smaller, the platform is raised. This makes a smaller passage between it and the breast-plate, and it is obvious that a less quantity of grain will cause the necessary 45 pressure to operate the tripping mechanism.

As soon as the disk d begins to move, the inclined side of the notch d^2 forces out the end of the clutch-shifting lever a^{10} , thus forcing out the pinion a^8 , and disengaging the clutches a^7 50 and a^8 . The packer-shaft a^4 and packers a^{12} are thus brought to rest. In this manner the packer mechanism and the binder mechanism are alternately in operation, the one being always in gear when the other is out of gear. 55 The binder-arm being in its lowest position, the cord v runs from the twine-box around the tension-pulley h^6 , thence around the guide-pulley at the bottom of the standard h' , thence over the guide-roller w and over the roller k^6 , 60 both the latter being fixed to the binder-arm near its pivotal point. From the roller k^6 the cord passes around the rollers k^8 and k^9 , and over the roller k^4 in the point of the binder-arm. It then passes upward over the edge of 65 the bar s and over the knotter-hooks, whence it passes to the grasper, where its end is held between the hook m' and the plate m^3 . The ten-

sion of the cord as it runs from the ball in the twine-box is regulated by the tension-roller h^3 . When sufficient grain has been accumulated 70 to form a bundle, the binder mechanism is set in motion, the binder-arm is raised, its point dividing the grain, and carries the cord around the bundle and up over the knotter-jaws and to the grasper. The finger k^{11} presses the 75 cord at a point between the gavel and the bar s . The cord is thus drawn taut and held so that it will pass under the wing o^2 of the knotter. The knotter revolves a little more than a complete rotation, forming a loop around the 80 jaws. Just before the knotter completes its revolution the jaws are opened by the lug o^7 coming in contact with the spring o^6 . The cords leading to the holder and point of the binder-arm then enter between said jaws. Just 85 before the completion of the forward movement the lug o^7 passes beyond the end of the spring o^6 . The knotter is then turned back by the teeth e^4 , and the jaws are closed by the spring o^6 , and hold the cords between them. 90 The holding-hook m' is now operated. It catches the cord and severs it against the knife m^8 , and holds the end running to the binder-arm between it and the plate m^3 , while the binder-arm returns to its lowest position, and 95 the two ends v' of the cut cord are freed. The loop v^2 around the jaws is now drawn off the jaws and over the ends v' by means of the stripper-hook s^2 , thus completing the knot. The compressor-arms b^3 are lifted, and the dis- 100 charger f revolves and pushes the bound bundle off the platform, drawing the ends of the cord from the knotter-jaws. The binder-arm is now thrown down. The rod c^2 and spring c^4 throw out the tripping-lever into the path 105 of the pawl d' , which pawl, coming into contact with said lever, is raised out of contact with the pins d^4 , and the binding mechanism is thrown out of gear and comes to rest. At the same time the end of the clutch-shifting lever a^{10} 110 drops into the notch d^2 , and the spring a^9 throws the pinion a^8 into engagement with the clutch a^8 and the shaft a^6 , and the packers are set in motion and the operation is repeated.

Having thus described my invention, what I 115 claim, and desire to secure by Letters Patent, is—

1. In a grain-binding machine, the combination of the breast-plate, a binder-table placed below it, and means, substantially as described, for adjusting said table vertically in relation to said breast-plate, whereby the passage-way for the grain may be enlarged or reduced, substantially as and for the purposes specified.

2. In a grain-binding machine, the combination of the platform composed of the fixed section g' and the hinged section g^2 , the slotted breast-plate g^2 , means, substantially as described, for vertically adjusting the section g^2 120 to reduce or increase the passage-way between it and the breast-plate, and the binder-tripping mechanism adapted to be actuated by the bulk of grain compressed between said 125 130

hinged section and the breast-plates, substantially as described, and for the purpose specified.

3. In a grain-binding machine, the combination of the compressor-bar g^3 , hinged at its inner end to the platform and having the longitudinal slot, and the binder-arm adapted to pass upward through said slot, and provided with the lifting-pin i , substantially as and for the purposes specified.

4. In a self-binder for harvesters, the combination, with the platform having a transverse slot or opening, of a compressor-bar placed within the opening and hinged at its inner end to the under side of the platform, its outer end supported flush with or slightly above the upper surface of said platform, and the binder-arm journaled beneath the platform, and provided with a pin adapted to engage said compressor-bar, substantially as and for the purpose specified.

5. In a grain-binding machine, the combination of a compressor-bar hinged at its inner end and extending outward under the grain, a resistance-plate arranged above said bar, leaving a space for the passage of the grain, and the binder-arm adapted to engage said compressor-bar and carry the same toward the resistance-plate, substantially as and for the purpose set forth.

6. In a grain-binding machine, the combination of the breast-plate, a vertically-adjustable binder-table arranged beneath said plate and provided with a transverse slot, means for vertically adjusting said table, a compressor-bar hinged to a fixed support and supported within said slot, and adapted in its normal position to rise and fall with said platform, and means, as described, for raising said compressor-bar above said platform, substantially as described.

7. The combination of the main shaft a , having a driving-pinion, a^2 , fixed thereon, the packer-shaft a^4 , provided at one end with cranks arranged over the passage-way for the grain, a fixed pin, b , slotted packer-arms a^{12} , carried by said cranks and engaging said pin, a clutch, a^8 , fixed to said packer-shaft, a sliding gear-wheel, a^9 , carried on the packer-shaft, meshing with the driving-pinion and provided with the clutch a^5 , a spring, a^6 , bearing upon one side of said gear-wheel, a disengaging-lever, a^{10} , bearing upon the opposite side of said sliding gear-wheel, and means, substantially as described, for automatically actuating the lever, substantially as set forth.

8. The combination of the main shaft and driving-pinion, the packer-shaft a^4 , packer-arms a^{12} , fixed pin b , a sliding gear-wheel and clutch carried by said packer-shaft, the binder-shaft a^6 , the disk d , fixed on said binder-shaft and provided with the notch d^2 , and the lever a^{10} , substantially as set forth.

9. The combination of the binder-shaft having a fixed disk, a spring-controlled pawl pivoted on the side of said disk, a loose gear-wheel carried on said shaft adjacent to the disk and

provided on its face with projecting pins adapted to engage said pawl, a trip-lever pivoted to the frame and adapted to disengage said pawl from the pins, the rod c^1 , and spring c^2 , for controlling said trip-lever, the crank on said binder-shaft, the slotted lever d^8 , having the segment-rack d^1 and delay-surface d^9 , the rock-shaft d^6 , provided with a segment-pinion, d^5 , the binder-arm k , and means for automatically operating the trip-lever, all constructed, arranged, and operating substantially as set forth.

10. In a grain-binding machine, the combination, with the packers, the binding-arm, the knotter, and the cutter and holder, of the driving-shaft a , having the pinion a^2 , the packer-shaft a^4 , provided with a clutch-half, a^8 , the loose sliding gear-wheel a^9 , carried on said packer-shaft and provided with the clutch-half a^5 , means for automatically engaging and disengaging the clutch, the shaft a^6 , the gear-wheel a^7 , loosely carried on said shaft a^6 and provided with the pins d^4 , the disk d , fixed on said shaft a^6 , the spring-pressed pawl d^1 , pivoted on said disk, the rock-shaft c , provided with the cam-levers c^1 c^2 , the trip-lever c^3 , fixed to said rock-shaft and adapted to engage said pawl d^1 , and the compressor-arms b^1 , b^2 , adapted to be pressed against the cam-levers, and thus actuate the rock-shaft, substantially as and for the purposes set forth.

11. In a grain-binding machine, the combination of the shaft a^6 , provided with the crank c^1 , the lever d^8 , having a slot engaging said crank and provided with a segment-gear, d^1 , and delay-surface d^9 , the rock-shaft d^6 , provided with the segment-pinion d^5 , engaged by said segment-gear and delay-surface, and the binder-arm fixed to said rock-shaft, substantially as and for the purposes set forth.

12. The combination of the hollow shaft n' , provided with the fixed hook or jaw o , having the pin o^5 , means, as described, for rotating said shaft forward and back, the shaft n^3 , provided with the jaw o^2 , having the slot o^4 and lug o^1 , and the spring o^6 , adapted to engage said lug, substantially as set forth.

13. The combination of the hollow shaft n' , provided with the pinion n^2 and the jaw o , the shaft n^3 , placed within the shaft n' and provided on its lower end with the jaw o^2 , extended outward under the jaw o and having its upper end extended above the pinion n^2 , the spring n^4 , supported by the upper end of the shaft n^3 and bearing upon the pinion n^2 , and the wheels e e^6 , arranged on opposite sides of the pinion n^2 and provided with segment-gears on their approximate faces, for rotating the said pinion and the shaft n' in opposite directions, substantially as described.

14. The combination of the knotter, the binder-arm, the cord holding and cutting device having the plate m^2 , provided with the opening m^1 , the knife m^3 , the pivoted hook m^4 , provided with the pin m^5 , and the wheel e , provided with the cam-groove e^3 , substantially as set forth.

15. The combination of the knotter, the binder-arm, the cord holder and cutter m , composed of the plates m^2 m^3 , having the opening m^1 , the rods m^4 , springs m^5 , knife m^6 , hook m' , provided with the pin m^7 , the cam-wheel e , and means for actuating said wheel and binder-arm, substantially as described.

16. In a self-binding harvester, the combination of the parallel plates m^2 and m^3 , coincidentally apertured to permit the passage of the point of the binder-arm, supports for said plates, springs arranged to press the plates together and permit their yielding, a blade, m' , arranged between the plates below said apertures, the hook m' , arranged to operate between the blade and the adjacent plate, its shank extending above the aforesaid apertures in the plates and pivotally attached to the upper end of the plate m^2 , and means, substantially as described, for automatically operating said hook, as and for the purpose set forth.

17. The combination of the shaft n' , provided with the jaw o , having the pin o^5 and the pinion n^2 , the spring n^4 , the shaft n^3 , provided with the jaw o^2 , having the slot o^4 and wing o^5 , the cord cutter and holder, the shaft a^6 , provided with the wheels e and e^6 , for operating said shaft n' and said cutter and holder, the binder-arm k , and intermediate operating devices, all constructed and arranged substantially as specified.

18. In a grain-binding machine, the combination of the cord-knotter, the bar s , pivoted on the frame and swinging below the knotter, the rock-shaft d^5 , arranged below the platform, the binder-arm k , fixed on the rock-shaft, its point when thrown up passing over the knotter-jaws, the finger k^1 , pivoted to the binder-arm and arranged to engage the binding-cord below the bar s , and means, substantially as described, for automatically actuating the said finger, substantially as and for the purposes set forth.

19. The combination, with the knotter and the cord-holder, of the swinging bar s , the rock-shaft d^5 , the binder-arm k , fixed on the said rock-shaft, the finger k^1 , pivoted on the binder-arm, the slotted bar k^2 , provided with the pin i^2 , and the fixed lug i^4 , provided with the eccentric slot i^3 , substantially as and for the purpose set forth.

20. In a self-binding harvester, the combination of the binder-arm, the finger k^1 , pivoted midway its length to the binder-arm, the actuating-bar k^2 , provided with a longitudinal slot placed over the binder-arm shaft, and its outer end pivoted to the inner end of the said finger, the pin i^2 , fixed on the side of said bar k^2 , and the fixed lug i^4 , having the eccentric slot i^3 , with which said pin engages, substantially as and for the purpose set forth.

21. The combination, with the knotter n , of the swinging bar s , the spring-controlled stripper-hook s^2 , pivoted on said bar, and the compressor-arm b^3 , adapted to operate said bar, substantially as set forth.

22. The combination, with the compressor-arms b^3 and arm b^2 , of the lifting-lever b , having pin b^9 , and the cam-wheels e and e^6 , substantially as set forth.

23. The combination of the compressor-arms b^3 , the knotter-operating wheels e and e^6 , provided with cam-grooves, and a lever connected by an intermediate arm to said compressor-arms and provided with a pin engaging the said cam-grooves, whereby said arms are raised to permit the ejection of the bundle, substantially as and for the purposes described.

In testimony whereof I affix my signature in presence of two witnesses.

PETER PAUL COLER.
